Specification for Design.

Patented Mar. 9, 1920.

Application filed July 24, 1919. Serial No. 313,113. Term of patent 7 years.

To all whom it may concern:

Be it known that I, PATRICIA M. CAREY, a citizen of the United States, residing at Los Angeles, in the county of Los Angeles and State of California, have invented a new, original, and ornamental Design for Dolls, of which the following is a specification, reference being had to the accompanying drawing, forming part thereof, in which:

The figure is a front elevation of a doll embodying the invention, the doll being shown in a sitting position.

I claim:

The ornamental design for a doll, as shown.
